UNITED STATES PATENT OFFICE.

HENRY HERBERT YELF, OF SOUTHSEA, PORTSMOUTH, ENGLAND.

SILENCING AND ANTICONCUSSIVE SUPPORT FOR TYPE-WRITING MACHINES AND THE LIKE.

1,079,037.

Specification of Letters Patent.

Patented Nov. 18, 1913.

Application filed August 29, 1912. Serial No. 717,739.

To all whom it may concern:

Be it known that I, HENRY HERBERT YELF, a subject of the King of Great Britain, residing at 43 Pelham road, Southsea, Portsmouth, in the county of Hampshire, England, have invented certain new and useful Improvements in Silencing and Anticoncussive Supports for Type-Writing Machines and the like, of which the following is a specification.

This invention relates to improvements in silencing and anti-concussive supports for typewriting machines and the like, and has for its object to provide improved simple and cheap devices of the kind applicable to the feet of typewriting machines and other machines in which noise is produced by the striking of keys or similar manipulations, which devices effectually deaden the sound and absorb the shock produced in working and thereby render the operation as silent as possible.

A further object of the invention is to provide supports of the character indicated in which the supports grip and are left attached to the feet of the typewriting machine when the latter is lifted about or is placed in or beneath its casing or cover.

According to this invention a pad which is readily attachable and detachable is provided for each foot of the typewriting machine and consists of a disk preferably circular of felt, india-rubber or like anti-concussive and non-resonant material, with a cover plate of metal, wood, celluloid, or other rigid material capable of distributing over the area of the anti-concussive disk the pressure of the foot due to the weight of the machine and the operation thereof. Upon the disk a clip such as a circular clip or circular series of grippers is provided for enabling the pad to be attached to the foot of the machine all as will be hereinafter particularly described and ascertained by reference to the accompanying drawings in which:—

Figure 1 is a side elevation of one form of anti-concussive support or pad constructed in accordance with these improvements. Fig. 2 is a plan of Fig. 1. Fig. 3 is a central vertical section of the pad seen in Figs. 1 and 2 secured to the foot of a typewriting machine or the like, the foot being shown in elevation and a portion of the base plate of the machine being shown in section. Fig. 4 is a

detail perspective view of the clip or gripper seen in Figs. 2 and 3. Figs. 5 and 6 are perspective views of anti-concussive supports or pads fitted with modified forms of clips or grippers.

In the various figures of the drawings *a* is the pad or support of anti-concussive or shock absorbing material and consists of a circular disk of felt, india-rubber or other suitable material and *b* is the cover plate of metal, wood, celluloid, or other rigid material capable of distributing over the anti-concussive disk the pressure of the foot of the machine due to the weight of the latter and to the operation thereof. Upon the disk *a* is fixed a clip, such as a circular series of spring grippers *c* Figs. 1 to 4 adapted to clip on to the foot *d* of the base plate *e* of a machine as shown in Fig. 4. The plate *b* is secured to the pad *a* by cementing or gluing or by punching or bending down small ears or clips (not shown) at the periphery of the plate so as to clip the felt, or both adhesive and clips may be used, and the grippers *c* are secured to the plate, as shown in Figs. 2 and 4, by passing a rivet *f* through such plate and through crossed blade spring members *g*, the end portions of which are bent upward so as to stand about vertically and form the circular series of grippers *c*. The free ends are bent downward and inwardly, as clearly seen in Figs. 3 and 4, so that the free ends *h* provide yielding surfaces for gripping the end of a foot *d* which is forced in between such yielding or spring portions *h*.

As shown in Fig. 5, the clip is formed of a ring composed of zig-zag or waved wire *j* some of the lower bends *k* of which are pinned, or riveted, as at *l*, or otherwise suitably fastened to the upper surface of the cover plate *b*, leaving the circular series of upper bends free for engaging with and gripping the foot of the typewriting machine. The clip seen in Fig. 5 thus resembles a spring wire basket into which the existing or usual foot of the typewriting machine is pressed.

As shown in Fig. 6, the foot of the machine is gripped by a clip consisting of two parallel pieces or strips *m* of waved or zig-zag wire which are fixed to the plate *b* by rivets *n*, in a manner similar to that described with reference to Fig. 5. In order to be engaged with a circular foot the strips

m would be bent outwardly away from one another to allow of the insertion of the foot, but they might, of course, be engaged with any other shape of foot, such as for example an oval, oblong or square foot.

Reverting now to Figs. 1 to 4 it will be seen that a cup or socket *o* is supported on the plate *b* by flange or wall *p* erected on the plate and secured by brazing or soldering to the cover plate *b*. The cup *o* and flange *p* are formed out of a disk or single piece of metal, the depth of the cup *o* is not so great as the depth of the flange *p* so that the bottom of the cup *o* lies a little distance above the cover plate *b*. The base of the flange *p* is expanded or enlarged, as at *q*. In this way the cup *p* is provided with an enlarged base upon which to stand so that the pressure of the foot *d* is distributed over a large area of the plate *b*.

The walls of the cup *o* are perforated or dotted, so as to allow the free ends *h* of the spider like gripper to pass into the cup *o* the radial portions *g* of the spider extending beneath the cup *o* and the vertical portions *c* extending upwardly outside of the cup. Thus the spring clip is hidden by the flange *p* and the whole device presents a very neat and finished appearance. The cup need not be round in plan but may be of any other suitable shape.

The feet of a typewriting machine of ordinary size fit into the cups *o* and are gripped by the springs *h* projecting into such cups and in addition to the pads absorbing the vertical shocks it will be seen that the spring tongues within the cups take up the small lateral shocks or the horizontal components of blows the incidence of which may not be

truly vertical. If the feet of a typewriting machine are too small for the spring tongues to grip them they may be fitted with rubber shoes, sleeves, or like adapters which will enable the grippers to engage the feet so that the machine can be lifted and carried about without losing its anti-concussive pads or supports.

What I claim and desire to secure by Letters Patent of the United States is:—

1. Silencing and anti-concussive supports for the feet of typewriting and like machines comprising a disk of shock absorbing or anti-concussive material, a cover plate permanently secured thereto, a cup supported by a surrounding wall or flange standing upon the cover plate, and a spring clip device secured to the cover plate beneath the cup having its arms bent upwardly outside of the cup and then downwardly and inwardly so that the free ends enter the cup through perforations or slots formed in the walls of the cup substantially as described.

2. An attachment for the feet of typewriting machines, comprising a pad of shock absorbing material, a cover plate fitted to said pad and co-extensive therewith, an upstanding flange member secured to the cover plate and bent upon itself to form a socket the walls of which are perforated, and spring clip member having a plurality of free foot engaging ends projecting through the opening in the socket walls.

In testimony whereof I affix my signature in presence of two witnesses.
